F. P. ATKINS

CANDLEWICK

Filed July 18, 1921

INVENTOR:

Frank P. Atkins

BY

Albert Heller
ATTORNEYS.

UNITED STATES PATENT OFFICE.

FRANK P. ATKINS, OF CINCINNATI, OHIO.

CANDLEWICK.

Application filed July 18, 1921. Serial No. 485,481.

To all whom it may concern:

Be it known that I, FRANK P. ATKINS, a citizen of the United States, and a resident of Cincinnati, in the county of Hamilton 5 and State of Ohio, have invented certain new and useful Improvements in Candlewicks, of which the following is a full, clear, and exact description, reference being had to the accompanying drawings, forming 10 part of this specification.

My invention relates to wicks for candles, and more particularly to wire cored wicks as used in sacramental paraffin candles.

In sacramental candles, which are made 15 of paraffin, there are two essentials, one of them being that the wick must be self-supporting, due to the early melting of the paraffin when the candle is left burning, and the other that the wick should burn evenly 20 without flicker or flare and for a definite time.

It is the object of my invention to provide a candle wick having a core of lead wire, and to so incorporate the twine of the 25 wick with the wire that a uniform structure results having just the correct burning quality and duration.

I am aware that cores of wire have been used in wicks, but am not advised of any efforts 30 prior to mine to make a perfect burning wick with wire. In fact, so great is the delicacy of the wicks that where the wick is unduly bent or handled, or the slightest variation in structure permitted, it will not 35 give the desired results. I find that I have to wind the wick on cores which are shipped with the wick on them without rewinding it from the braiding machine, as otherwise the wick quality cannot be guaranteed.

40 I accomplish my objects by that certain construction and arrangement of parts to be hereinafter more specifically pointed out and claimed, wherein I braid the twine over a straight core of wire, said twine being of 45 single ply, and the braid being four sided, and twisting being entirely avoided.

In the drawings,

Figure 1 is a diagrammatic view showing the braiding operation.

50 Figure 2 is a much enlarged view of the braided wick.

Figure 3 is a diagrammatic view illustrating the square nature of the braid, the threads or twine being much enlarged.

55 I have not attempted to show a complete braiding machine, nor the method of draw-

ing the wick material through the former plate over tension rolls and onto the shipping spool. It will be understood that driven rolls draw the various threads of the 60 wick including the lead wire core through a plate having a single hole therein, of approximately the desired diameter of the wick, whence the wick passes onto the driven rolls, which are faced with emery cloth to 65 prevent slipping. Several turns around the rolls are made in the wick, after which it is guided to a winding shaft which rolls it up on a removable fibre spool, upon which the 70 wick is shipped.

These operations, with the exception of the emery cloth on the rolls and the removable fibre spools or cores, are used in twine braiding machines as a familiar practice, and need not be detailed to those skilled in 75 the art.

I have merely illustrated the nature of the braid by showing in Figure 1 eight spools of which the spools 1 move around a figure 8 path as at 2, and the spools 3 80 move around a like path 4.

Single ply twine is mounted on these spools so that eight pieces of single ply twine are used in the wick as distinguished from, say four pieces of double ply twine, 85 which would give a wick of equal diameter, but in which there would not be any guaranty of uniformity, due to unevenness in the double ply and the difficulty of handling double ply twine in a perfectly uniform 90 manner in a braiding machine.

As was noted the threads of twine are passed through a hole 5 as they are drawn from the spools during the spool movement, said spools passing each other and each 95 spool 1 acting to lay its thread across each spool 3 during the operation.

The result of moving the spools in the manner described and withdrawing the twine through the former plate at the same 100 time is to form a square braid, in which the threads cross each other at 6, 7, 8, and 9, at the points where the spools pass each other.

By referring to the threads of single ply twine as *a*, *b*, *c*, *d*, *e*, *f*, *g*, and *h*, it will be noted that thread *a* passes under thread *b*, and at the same time thread *c* passes over thread *d*, and so on, as per the diagram in Figure 3. At the next braiding step the 110 thread 2 will have taken the place of thread *c* and will pass over its companion thread

which will be the case all the way around the pattern.

During this braiding operation the lead wire 10 is drawn straight up from the intermediate space 11 between the spools, forming an unbent core or center for the braid with the braid formed closely about it. After the completed braid with the lead core comes to the emery faced rolls it naturally is bent, but no kinks or breakage can occur in the wire at this stage.

In making up the candle a hole is left in the paraffin stick, and the wick thrust up through the hole, after being paraffin-coated itself. The entire product is placed in a glass container, which will hold the paraffin when it is melted, the wick having some kind of a plate on its lower end to hold it upright.

These features however form no part of my invention, which consists in the wick of single ply twine braided over a straight piece of lead wire. In burning, the wire melts as the wick is expended, and with a wick of the character produced as above, the burning time can be calculated down to minutes of time, and the flame indoors, out of draft, will be constant and fairly low.

This adapts the wick perfectly for sacramental purposes, where candles must never go out and leave the sacred place in darkness, and where an even low flame is required.

The lead core is of a diameter only slightly larger than the individual pieces of single ply twine.

Having thus described my invention, what I claim as new and desire to secure by Letters Patent, is:—

1. A candle wick for the purpose described, comprising strands of single ply twine tightly and uniformly braided about a straight core of bendable and expendable wire, such as lead wire.

2. A candle wick for the purpose described, comprising strands of twine closely braided in a square pattern over a straight core of bendable and expendable wire, such as lead wire.

3. A candle wick for the purpose described, comprising eight single ply strands of twine, braided closely in a square pattern over a straight core of bendable and expendable wire, such as lead wire.

FRANK P. ATKINS.
